UNITED STATES PATENT OFFICE.

WALTER L. BEATTIE, OF MILWAUKEE, WISCONSIN.

COMBINATION SPRINKLER AND HOSE CARRIER.

Application filed November 23, 1922. Serial No. 602,800.

To all whom it may concern:

Be it known that I, WALTER L. BEATTIE, a citizen of the United States, and resident of Milwaukee, in the county of Milwaukee and 5 State of Wisconsin, have invented certain new and useful Improvements in Combination Sprinklers and Hose Carriers; and I do hereby declare that the following is a full, clear, and exact description thereof.

10 This invention relates to a combination sprinkler and hose carrier.

Objects of this invention are to provide a combined hose carrier and sprinkler; to provide a device which is portable, which is self supporting at all times, and may be freely moved into position; to provide a device upon which the hose may be readily wound; and to provide a sprinkler and hose carrier which does not necessitate soiling of 20 the operator's hands in manipulating the device either before or after use.

Further objects are to provide a combined sprinkler and hose carrier of strong and rugged construction, which may be cheaply 25 and readily produced and which will have a relatively long life.

An embodiment of the invention is shown in the accompanying drawings, in which—

30 Figure 1 is a side elevation of the apparatus showing it in connected position.

Figure 2 is a transverse sectional view thru the reel.

Figure 3 is a sectional view taken on the line 3—3 of Figure 1.

35 Figure 4 is a fragmentary detail of the construction of one of the corners of the apparatus.

The device comprises a framework formed of bottom longitudinal members 1, 40 transverse bottom members 2, and four uprights 3. The uprights 3 are secured to the upper longitudinal members 4, and to the transverse upper members 5. A convenient way of forming the joints between the members is illustrated in Figure 4, from which it will be seen that the uprights are positioned against the longitudinal members with their flat faces in contact, and are secured in such position by means of bolts 6. The transverse members 5 are positioned with their flat faces in contact with the narrower faces of the longitudinal members, and are secured to the uprights by means of bolts 7. This provides a very strong construction

and one which will not readily give at the 55 corners.

To further strengthen the framework and to provide a support for the reel, a pair of diagonally arranged bracing members 8 and 9 are positioned between the upper and 60 lower longitudinal members 1 and 4. These members 8 and 9 may be formed from strap metal with their terminal portions twisted and angularly extended to provide attaching feet 10. Screws or other fastening 65 means 11 are passed thru suitable apertures in these feet and into the longitudinal members to thereby rigidly secure the bracing and supporting diagonal members in position. This, as will be seen, provides a 70 sturdy brace against any folding or collapsing motion of the side frames.

A front axle 12 is secured beneath the lower transverse members 1 in any suitable manner, and carries forward wheels 13. The 75 rear portion of the apparatus is supported by a castor comprising a forked member 14 provided with a wheel 15 and having an upwardly extending projection 16 pivotally received in an aperture thru the forward 80 transverse member 2. In order to provide suitable bearing surfaces for the pivot 16, a pillar block 17 is bolted to the under side of the forward transverse member 2, as may be seen from Figures 1 and 3. 85

A reel is supported between the braces 8 and 9 for the sides of the framework and comprises circular disks 18 reinforced by intersecting diagonally arranged reinforcing strips 19, such strips being mortised, as indicated at 20. Transverse bars 21 are arranged in abutting contact with the end disks 18 and have their edges bevelled, as indicated at 22, and secured to the diametrically arranged reinforcing bars 19, as may be seen from Figure 2. The reel is supported upon the squared portion 23 of a transverse shaft, whose terminal rounded portions 24 are suitably journaled in the bracing members 8 and 9 at their intersection. One of the terminal portions is extended and has the hub 25 of a crank 26 rigidly secured thereto. A clip 27 is secured to one of the reinforcing members 19 of the reel, and is adapted to receive the end 28 of the hose when the hose is being wound upon the reel. This clip, it will be seen from Figures 2 and 3, is adapted to grip and securely

retain the end of the hose between itself and the reinforcing member 19, and to permit the ready removal of the hose therefrom. A similar clip 29, indicated in dotted lines in Figure 1 and in full lines in Figure 3, is provided for the other end of the hose.

The sprinkler comprises a sprinkler head 30 mounted upon an elongated longitudinally arranged pipe 31, which is connected 10 with a short vertical pipe 32 by means of a manually controlled valve 33. The lower end of the pipe 32 is threaded to receive the hose fitting 34, as indicated in Figure 1.

The operation of the apparatus is as follows:—The apparatus is either rolled to the position where it is to be used, or to the hydrant and the end of the hose connected with the hydrant. Thereafter it is moved to its desired position, thereby allowing the 20 hose to unwind and to be laid across the lawn without damaging the shrubbery or otherwise marring the lawn by dragging the hose across it. After the apparatus has been correctly positioned, the end 28 of the hose 25 is coupled to the pipe 32, as indicated in Figure 1. The water flow may be accurately adjusted by means of the valve 33 while the operator is close to the flowers which are being sprayed, and may observe the action 30 of the apparatus and secure the exact flow of water desired.

When it is desired to rewind the hose, the end 28 is caught between the clip 27 and the reinforcing member 19, and the apparatus

pushed towards the hydrant while the crank 35 26 is being rotated, thereby rewinding the hose without dragging it across the lawn.

It will thus be seen that a combined hose carrier and sprinkler has been provided which is efficient in operation, easily manipulated and of rugged and lasting construction.

I claim:

1. A hose reel comprising a framework, a plurality of supporting wheels therefor, 45 diagonally arranged crossed braces secured to said framework, a reel mounted between said braces, a shaft for supporting said reel and having bearing relation with said braces at their points of crossing, and a crank 50 mounted upon said shaft and adapted to operate said reel.

2. A hose reel comprising a framework, a plurality of supporting wheels therefor, 55 diagonally arranged crossed braces secured to said framework, a reel mounted between said braces, a shaft for supporting said reel and having bearing relation with said braces at their points of crossing, said reel comprising end disks and diagonally arranged 60 bracing members secured thereto, and transverse bars having bevelled edges secured to said bracing members.

In testimony that I claim the foregoing I have hereunto set my hand at Milwaukee, in 65 the county of Milwaukee and State of Wisconsin.

WALTER L. BEATTIE.
